REVERSING DEVICE FOR MULTICYLINDER INTERNAL-COMBUSTION ENGINES.

1,017,350.

Specification of Letters Patent.

Patented Feb. 13, 1912.

Application filed August 24, 1911. Serial No. 645,810.

To all whom it may concern:

Be it known that I, GUSTAV HEINRICH WILHELM UREN, engineer, a subject of the King of Prussia, German Emperor, residing 5 at Aachen, in the Kingdom of Prussia and German Empire, have invented certain new and useful Improvements in Reversing Devices for Multicylinder Internal-Combustion Engines, of which the following is a 10 specification.

My invention relates to multi-cylinder internal combustion engines and the object of my invention is to provide improved means for effecting reversal.

15 According to my invention, only a single fuel supply pipe is provided for each cylinder and, in connection therewith, only one fuel supply device and one actuating member therefor. When the engine is to be reversed, the actuating members for the fuel supply devices are shifted in such a way that some of the actuating members will act on the fuel supply devices of oppositely acting cylinders. After the reversal has been 20 effected, all the actuating members are automatically returned to their initial positions.

Moreover, according to my invention, a larger amount of fuel is supplied to the cylinders, when the engine is reversed, 25 whereby a richer mixture is produced, so that, even at a low degree of compression, the mixture is ignited with certainty during the compression stroke.

The drawing shows one of the cylinders 30 of a four-cylinder engine and the fuel supply devices together with the operating devices therefor.

It is assumed that the cranks of the first and fourth cylinders are similarly disposed 35 and those of the second and third cylinders set at an angle of 180° relatively to the former.

It is also assumed for the sake of simplicity that the invention is applied to a 40 two-cycle motor. In this case the power strokes follow each other at intervals of 180° each and the first and fourth cylinders and the second and third cylinders operate simultaneously.

50 The fuel supply members *a b c d* belonging to the four cylinders respectively are operated in any convenient manner *e. g.* by the cams *e f g h*, the cam *e* operating the fuel supply member *a* connected with the first

cylinder, the cam *f* the fuel supply member *b* connected with the second cylinder, the cam *g* the fuel supply member *c* connected with the fourth cylinder and the cam *h* the fuel supply member *d* which is connected with the third cylinder. The cams are 55 driven by a motor shaft and can be adjusted, for reversing purposes, in any convenient manner. In the constructions as shown a fork *i* fixed to a slide bar *k* is employed.

The slide bar *k* is connected with a device 60 of a known type which, after reversal has taken place, will return the operating devices of the fuel supply devices to their original positions.

In the drawing a link *l* is shown which 65 link is connected with a slotted lever *m*. The slot *m* is centrally pivoted at *n* and is pivotally connected by a rod *o* with a bushing *p* rotatably mounted upon the driving shaft *w*. This bushing is split and is 70 held together by spring pressure so that owing to slight frictional contact with the shaft it is driven by the latter. In order to limit the movements of lever *m*, two stops *r* and *s* are provided as shown. A rod *t* 75 pivotally connects the link *l* with the hand lever *v* which is pivoted at *u* and serves for reversing the engine.

Reversal is effected in the following manner: By pulling the lever *v* to the right into 80 the position marked "Backwards" the lower end of the link *l* is moved upward in the slot of lever *m* and the rod *k* with the fork *i* and the cams *e f g h* are raised to such an extent that *f* and *h* now act upon the fuel 85 supply members *a* and *c* of cylinders I and IV. Suitable devices can be interposed to prevent the cams *f* and *h* from operating the fuel supply members *a* and *c* until the speed of rotation has been sufficiently reduced. As the cams *f* and *h* are arranged 90 at an angle of 180° relatively to the cams *e* and *g*, fuel is supplied to the cylinders I and IV the pistons of which are approximately at the lower dead center. Thus premature 95 ignition is caused the pistons are driven back and thereby the engine is reversed. As soon as the crank shaft rotates in the opposite direction, however, the bushing *p* is rotated in the same direction by the driving shaft *w* and the rod *o* and lever *m* are drawn downward against the stop *r*. As 100 lever *m* is connected by *l*, *k* and *i* with the

cams, the latter are returned to their initial positions and operate the fuel supply members in such a manner that fuel admission again takes places at the normal time. As 5 a result the motor continues to rotate in the reversed direction.

In order again to cause the motor to run in a forward direction, the lever *v* is brought into the forward position after which the 10 operation just described is repeated.

By a constructional modification either the fuel supply members or the operating cams can be so formed that during reversal a larger quantity of fuel is supplied to the 15 operative cylinders. In the construction as shown the stroke ratios of the cams are different, the stroke of the cams *f* and *h* being greater than that of the cams *e* and *g*. In forward and reversed running this exerts 20 no influence upon the stroke of the fuel supply members as the effective stroke of the fuel supply members is calculated in such a manner as to deliver always equal quantities of fuel. As soon, however, as the 25 cams *f* and *h* are shifted so that they will operate the fuel supply members *a* and *c* when reversing the difference of stroke exerted on these members will be noticed as a larger quantity of fuel will be supplied. 30 The richer mixture thereby produced largely assists in producing rotation in the reversed direction as a richer mixture can be ignited at a lower compression and the backward stroke of the piston is effected with greater 35 certainty.

The fuel supply members may be mounted in any other relative positions and they may be operated by cams, or the like, directly or with the inter-position of transmitting gear such as levers or the like. The 40 fuel supply device can also be constructed in such a manner that the fuel is injected

into the cylinders with the use of compressed air or the like.

I claim:

1. Reversing mechanism for multi-cylinder internal combustion engines, comprising, in combination with the cylinders, fuel supply devices, one for each cylinder, an actuating member for each fuel supply device, and means for operatively connecting some of said actuating members with the fuel supply devices of oppositely acting cylinders for the purpose of reversing the engine. 45

2. Reversing mechanism for multi-cylinder internal combustion engines comprising, in combination with the cylinders, fuel supply devices, one for each cylinder, an actuating member for each fuel supply device, means for operatively connecting some of said actuating members with the fuel supply devices of oppositely acting cylinders for the purpose of reversing the engine, and means for automatically returning the 60 actuating members to their initial positions. 55

3. Reversing mechanism for multi-cylinder internal combustion engines comprising, in combination with the cylinders, fuel supply devices, one for each cylinder, an actuating member for each fuel supply device and means for operatively connecting some of said actuating members with the fuel supply devices of oppositely acting cylinders for the purpose of reversing the 70 engine, said actuating members being so constructed as to supply an increased amount of fuel when the engine is reversed. 75

In testimony whereof I have affixed my signature in presence of two witnesses.

GUSTAV HEINRICH WILHELM UREN.
